UNITED STATES PATENT OFFICE.

FRANK TAYLOR, OF ROCHESTER, NEW YORK.

DESIGN FOR A SCALE.

SPECIFICATION forming part of Design No. 30,939, dated June 6, 1899.

Application filed March 28, 1898. Serial No. 675,505. Term of patent 7 years.

To all whom it may concern:

Be it known that I, FRANK TAYLOR, a citizen of the United States, and a resident of Rochester, in the county of Monroe and State 5 of New York, have invented and produced a certain new and original Design for a Scale, of which the following is a specification.

This invention relates to a design for a scale for thermometers and other measuring instruments; and it consists in the new and original scale substantially as herein shown and described.

In the drawing, A are parallel lines indicating the greater graduations, and B are sets of 15 equal numbers of parallel lines parallel to and between each pair of adjacent lines A A. The lines B B, indicating the smaller graduations, are arranged in sets alternating on the two sides of the middle vertical line of the 20 scale and at right angles to the imaginary middle line thereof. In other words, between any two successive lines indicating a greater graduation is a set of parallel lines B B, indi-

cating the smaller graduations, extending outward in one direction from the imaginary 25 middle line of the scale, and between the lines A A, representing the next greater graduation, is another set of parallel lines B B, which extend outward and in the other direction from said imaginary middle line. Parallel 30 vertical side lines C C, to which the lines A and B are perpendicular, extend continuously on the outer edge of the graduation-lines B B, as shown. The alternate lines A A extend slightly outside of the vertical lines C C. 35

The leading feature of this design is the scale having the graduation pattern consisting of the lines A A, B B, and C C.

What I claim is—

The design for a scale herein shown and described. 40

FRANK TAYLOR.
